ARTICLE BURNISHING MACHINE

Clarence C. Kinker, Manitou Beach, Mich., and James J. Murtagh, Toledo, Ohio, assignors to Gerity-Michigan Corporation, Adrian, Mich., a corporation of Michigan

Application May 20, 1953, Serial No. 356,292

9 Claims. (Cl. 51—138)

This invention relates to machines and a method for 15 buffing, burnishing and polishing metal articles to improve the surface finish either in preparation for the application of protective coatings thereto or for use directly as taken from the machine. The invention is directed particularly to improvements of the invention claimed in our Reissue Patent 23,715, dated September 29, 1953.

While the machine of said patent is highly efficient in its operation on relatively small articles, it is difficult to use it for the treatment of long articles such as automobile bumpers because of the large tank diameter required. It is, therefore, the primary purpose of the present invention to provide a machine of this character wherein the operations of buffing, burnishing and polishing are performed in a straight line movement of the article, thus enabling elongated articles of considerable length to be processed in a rapid, efficient and economical manner.

Another object of the invention is the provision in a machine of this character, of an endless type of flexible buffing or polishing head for acting on the work while the work is in contact with the abrasive of a burnishing liquid, and which preferably comprises a plurality of resilient belt sections operating side by side so that the work contacting surfaces thereof may accommodate themselves more perfectly to the contours of the work acted on. In other words, the several sections may separately ride higher or lower over the work to suit the surface configuration thereof.

Another object of the invention is the provision in combination with a multiple section buffing or polishing belt of the character described, of means for causing the liquid suspended abrasive materials to be drawn from one or both side edges of the belt and distributed over the entire surface of the work-piece being acted on. In this manner the abrasive is prevented from settling out in an inactive portion of the tank in which the liquid suspension is contained.

Another object of the invention is to provide an improved method of burnishing, buffing or polishing the surface of formed metal articles.

Other objects and advantages of the invention will be apparent from the following detailed description, and from the accompanying drawings illustrating one embodiment of the invention, and in which—

Fig. 1 is a plan view of the machine taken as indicated by arrows 1 in Fig. 2, with parts broken away.

Fig. 2 is an enlarged sectional and elevation of the machine taken on the line 2—2 in Fig. 1, with parts broken away;

Fig. 3 is an enlarged fragmentary plan view of one of the sectional buffing or polishing belts employed;

Fig. 4 is an enlarged fragmentary section on the line 4—4 in Fig. 1;

Fig. 5 is an enlarged fragmentary sectional side elevation on the line 5—5 in Fig. 1, with parts broken away;

Fig. 6 is an enlarged side edge view of a work-carrying

2

plate removed from the conveyor, with parts broken away and with a work-piece shown in dotted lines as mounted thereon;

Fig. 7 is an enlarged fragmentary section through the conveyor chain axially of a pivot member thereof, as on the line 7—7 in Fig. 5, with parts in full;

Fig. 8 is an enlarged section on the line 8—8 in Fig. 2;

Fig. 9 is an enlarged plan view taken on the line 9—9 in Fig. 2;

Fig. 10 is an enlarged section on the line 10—10 in Fig. 2, and

Fig. 11 is an enlarged section taken on the line 11—11 in Fig. 2.

Referring to the drawings, 1 designates an elongated table that is mounted in transversely inclined position on a sub-structure 2, the inclination to a horizontal being approximately 20° in the present instance. An endless conveyor chain 3 for carrying the articles or work-pieces to be burnished is mounted for travel over the top surface of the table 1 and has front and rear transversely spaced end-connected runways at different elevations due to the inclination of the table.

The front or lower run of the conveyor is through a burnishing compartment 4 containing a liquid suspension of an abrasive material 5 in which the conveyor and carried work-pieces are at least partially submerged and wherein the burnishing operation takes place, as hereinafter described. The compartment 4 is formed at its bottom by the table 1, at front and back by the side walls 6 and 7, respectively, and has open ends 8 and a top 9. At each end of the compartment 4 is an open-top extension 10 that is open to the compartment and is angled to follow for a distance the conveyor run at each end to a point above the normal level of the burnishing liquid. The upper run of the conveyor is through a channel 11 formed by the table 1 and by front and rear walls 12 and 13, respectively, and at the center of this channel, lengthwise thereof, is through a tunnel portion 14 in which washing of the burnished work-pieces takes place. The wall 12 is shallow and formed, in the present instance, by a flange of an angle bar. The removal of the burnished articles from the conveyor and the replacement by others take place after the articles pass from the washing tunnel 14, which, in the present instance, is at the left of the compartment.

The conveyor 3, in the present instance, comprises successive alternating pairs of vertically spaced links 16 and 17, with the successive pairs connected at their ends by pivot bolts 18 (Figs. 5 and 7). The bolt 18 shoulders against the spaced links 16 of each pair to hold the links axially spaced and has at its lower end a clamping nut 19 and at its upper end a stud nut 20. A sleeve 21 is mounted on each bolt 18 in end abutment with the respective links 16, and its ends are reduced a short distance to form spaced bearings for an associated pair of links 17 at the adjacent ends thereof, as best shown in Fig. 7. A gasket 22 is mounted on each end of the sleeve between the adjacent links 16 and 17 and serves to seal and protect the link joints from the abrasive action of the burnishing liquid. The axes of all of the conveyor bolts 18 are normal to the inclined surface of the table 1, and there is, therefore, no tilting of the pivot bolts relative to the links as they traverse the course.

The conveyor chain 3 is guided in its course by corner sprocket wheels 25 disposed in pairs at each end of the table between the front and rear runways, and also by smaller idler wheels 26 in said runways. These wheels are mounted on studs 27 rising from the table 1 normal thereto. In the lower or front run, the idler wheels 26 alternate at opposite sides of the conveyor, thus tending to cause the conveyor to maintain a set course, and par-

ticularly to prevent lateral deflection thereof in its passage through the burnishing compartment 9.

The guide wheels 25 and 26 are preferably in the form of sprocket wheels, being provided in their peripheries with notches 28 which receive the pivot sleeves 21 of the conveyor intermediate the links 17 of each pair as the conveyor traverses its course.

The present drive for the conveyor is from a motor 30 through a belt to a variable speed drive designated generally 31 (Fig. 2) and thence from the shaft of said pulley through a speed reduction unit 32 to a shaft 33. This shaft extends up through a bearing 34 in the table 1 and has a pinion 35 at its upper end in driving mesh with an internal gear 36 (Figs. 2 and 4) on the under side of one of the guide wheels 25, the upper left hand one in the present instance. The motor 30 is mounted in a guide 37 to permit adjusting movements thereof to tighten the belt, and adjustment is effected by turning a hand wheel 38 the shaft of which is threaded in the motor base.

The conveyor chain 3 carries on its top edge a plurality of successively positioned work-carrying plates 40 on which work-pieces A to be burnished are mounted and securely held in any suitable fixture or by edge clamps 41 (Fig. 6). These carriers may be of any desired size and shape to suit the size and shape of the work-piece to be carried thereby and each is provided on its under side with downwardly projecting studs 42 and 43 adjacent to respective opposite ends thereof, the stud 42 having a socket 44 therein of slot-like form lengthwise of the carrier plate 40 while the stud 43 has a pivot socket 45 therein. The sockets 44 and 45 are normal to the plane of the plate 40 and each is adapted to receive a registering stud 20 of the conveyor. The spacing of the socket studs 42 and 43 depends on the length of the carrying plate 40 and also the spacing of the conveyor studs 20 on which the respective sockets are mounted. If the carriers 40 are short, the sockets may engage over the studs 20 at opposite ends of a single pair of links 16, and if of greater length so that the carrier plate spans a number of links, the socket studs may be so positioned as to engage studs which are spaced one or more links apart lengthwise of the conveyor. The transversely elongated socket 44 permits movement of an engaged stud therein lengthwise of the plate so as to compensate for differential movements of the sockets and studs that occur when the associated conveyor links are passing from one straight runway to the other of the course and also to prevent binding of the studs in the sockets. The studs 20, while having free pivotal movements in the respective sockets 44 and 45, serve to brace the carrier plates against lateral tilting movements relative to the conveyor. Tilting of the carrier plates 40 in their passage through the burnishing compartment 4 is further prevented by a series of side edge supporting rolls 47 mounted on the bottom of such compartment, as shown in Fig. 2.

The burnishing compartment 4 may have one or more burnishing units B therein spaced lengthwise of the conveyor belt so as to perform separate burnishing operations on the work-pieces as they are moved through said compartment by the conveyor. In the present instance, two of these units are shown, and inasmuch as they are duplicates, so far as general construction and operation are concerned, only one will be described. In practice, successive burnishing units are moved in opposite directions, one clockwise and the following one counterclockwise so that the work, as it is moved slowly beneath the belts, is acted upon in such a manner that all surfaces are completely burnished. If only a single belt were used, it would be possible for a projection, for example, to shield the surface immediately behind it to such an extent that the shielded area would be imperfectly burnished.

The burnishing heads, in the present instance, are disposed at opposite sides of a transverse center line through the machine, and each includes an endless burnishing belt 50 which is guided for movements lengthwise of the

associated conveyor run by spaced drum-like pulleys 51, one of which is mounted on a stub shaft 52, while the other is mounted on a drive shaft 53. Both project forward from a beam-like frame structure 54 (Figs. 1, 2 and 5). The burnishing belt 50 preferably comprises a plurality of sections disposed side by side as shown in Fig. 3, and each section is provided on its outer surface with a multiplicity of abrading projections 55 which, during their lower run with the belt, engage the top surface of the work-pieces A as they pass thereunder with the conveyor while the work is submerged in the burnishing liquid 5, as shown in Fig. 5. The continuity of the projections 55 on the belt sections is interrupted at intervals by diagonally disposed ribs 56 thereon disposed to direct the burnishing liquid transversely toward the central portion of the belt. The burnishing liquid is thus distributed substantially uniformly to all portions of the exposed work surface. By establishing a flow of burnishing liquid from the sides toward the center of the burnishing compartment 4 the suspended abrasive material is kept from settling out. The belt sections are of rubber or other suitable pliable material, and the projections 55 are sufficiently stiff to apply a rubbing action of the abrasive material against the surface of the work and to reach crevices thereof, and the degree of flexibility may be changed by altering the length and cross section of the fingers to alter the force of the rubbing action.

The frame structure 54, which is of hollow beam-like form, is mounted for transverse rocking movements 30 on a shaft 57 that is mounted at its opposite ends in respective slide-bars 58, which, in turn, are mounted in and guided for longitudinal reciprocatory movements in a plane normal to the table 1 by stationary uprights 59 that rise from the sub-frame structure 2 and extend upward, 35 through and above the table 1. It is thus apparent that a rocking of the frame structure 54 on the shaft 57 will effect a corresponding transverse rocking of the burnishing belt 50 and its pulleys 51. This rocking action enables the burnishing surface of the belt to be transversely adjusted relative to the conveyor and work carried thereby to suit the surface configuration of the work. The slide-bars 58 are retained in their respective guideways by cross-pieces 59a.

The frame 54 has a pair of longitudinally spaced bracket arms 60 projecting rearwardly and upwardly therefrom 45 and connected at their upper ends to form a supporting bracket for a motor 61. The drive shaft 53 has bearings in and projects rearwardly through the beam 54 between the two arms 60 and carries a pulley 62 that is connected 50 by a belt 63 to the motor drive pulley 64. The belt 63 also passes around an idler pulley 65 that is mounted on a stud projecting rearwardly from the member 54, and which may be adjustable in a conventional manner for belt tightening.

For the purpose of obtaining a rocking adjustment of 55 the frame member 54 and parts carried thereby, one of the bracket arms 60 is pivotally connected at 66 (Figs. 2 and 11) to the lower end of a link 67 that extends up at one side of the motor 61 and is pivotally connected at 60 its upper end to one arm of a bell-crank lever 68. This 65 lever is pivoted at 69 to the upper end portion of the adjacent slide-bar 58. The lever 68, in the present instance, is composed of two transversely spaced duplicate parts (Fig. 9) between which the bar 58 is received and which also receive the upper end of the link 67 therebetween. The other or upwardly extending arm of the lever 68 has a nut member 70 pivotally mounted between its two side members, and the threaded stem 71 of a control wheel 72 is threaded through this nut. The inner end of the stem 71 adjacent to the control wheel is provided with a sleeve 73 in which it turns, and this sleeve 70 is pivotally mounted for vertical rocking movements between a pair of fork arms 74 on the upper end of the right hand slide-bar 58. It is thus apparent that a turning 75 of the control wheel 72 will impart a rocking move-

ment to the lever 68, which movement in turn will be transmitted through the link 67 to the bracket arm 60 and frame member 54, thereby effecting a corresponding rocking of the shafts 52 and 53, the belt carrying pulleys 51 and the belt 50 mounted thereon. The positioning of the motor 61 at the opposite side of the frame rocking axis 57 to the burnishing means serves as a counterbalance for the frame.

The two slide-bars 58 are each provided on their forward edges near their upper end portions with a series of rack teeth 78 with each of which a pinion 79 on a cross-shaft 80 meshes (Figs. 2, 5 and 8). A worm wheel 81 (Fig. 8) is mounted in a case 82 on the outer end of the shaft 80 and is engaged by a worm 83, the shaft 84 of which carries a control wheel 85. The case 82 is attached 15 to the upper end of the right hand frame upright 59.

It is apparent that a burnishing unit, which includes the pulleys 51 carrying the burnishing belt 50, the two slide-bars 58, frame members 54 and motor 61, is adjustable to raise and lower the belt to suit its position to the work to be operated on by simply turning the hand wheel 85, which effects a turning of the pinions 79. Thus the pressure exerted by the belt against the work may be varied in this manner as well as by changing the stiffness of the projecting fingers. In most instances it will be desirable to leave the center portion of the active run of the belt unsupported between the pulleys so that more perfect accommodation of the contour of the belt to the contour of the work will result. However, a backing plate may be provided for the lower belt run, if desired.

Each upright 59 is rearwardly braced by a frame member 88 which extends rearwardly and downwardly and attaches at its lower end to a respective frame bar 89 rising from the sub-frame structure 2 in advance of the spray tunnel 14 (Figs. 1 and 2).

The tunnel 14 is provided interiorly with pipes 95 extending from a suitable source of water pressure supply, and these pipes, in the present instance, are perforated or provided with a series of nozzles for directing spray streams therefrom onto the work-pieces A as they traverse the tunnel with the conveyor. Obviously the water supply may be taken from a source of treated water if desired, to promote wetting and cleaning of the burnished pieces.

The drippings from the conveyor, which may carry suspended abrasive particles, after passing from the lower right hand end of the runway to the elevated portion 11, are returned to the liquid in the runway 10 by flowing down the inclined bottom surface of the runway portion 11, such action being assisted by the tapered wall or flange 12 at the inner edge of the portion 11 and which is disposed at the rear of the entrance end of the tunnel. The wall or flange 12 in advance of the rear edge of the tunnel 14 in the direction of movement of the conveyor is inclined in opposite directions to a discharge opening 96 in the bottom of the runway 11 so as to direct the washing spray drippings from the tunnel 14 and from the work after leaving the tunnel toward such opening. The liquid discharging through the opening 96 is directed into a sump tank 97 beneath the central rear elevated portion of the floor 1. The rear edge of the opening 96 is provided with a directing flange 98 and the forward edge of the opening is provided with a barrier flange 99 and these flanges cooperate to direct the discharge water into the sump chamber 97 rearwardly of a weir 100 which divides the chamber into a settling compartment and a clear water compartment. A drainage pipe 101 leads from the upper portion of the clear water compartment to any suitable source of disposal.

In the operation of the machine, articles to be burnished are mounted on the conveyor plates 40 at the upper left hand portion of its run, or forward of the spray tunnel 14, and thence pass with the conveyor forwardly and downwardly into the lower liquid containing compartment 4 and under the successive burnishing belts

70 75

50, which act on the work-pieces to impart the desired burnishing operation thereto while submerged in the liquid. The compartment 4 is previously filled with a liquid (preferably water) suspension of suitable abrasive material depending on the metal to be burnished, the character of the finish desired and other factors. Finely divided alumina and silica abrasives mixed with cork flour and cork granules have been found suitable, and surface tension reducing agents may be added to promote wetting. In the appended claims, the suspension of abrasive and other materials is referred to as a "burnishing liquid." The flexible rubber projections 55 on the belt 50 conform to the irregular shape of the work and reach into crevices thereof during the burnishing operation. The sectional feature of the burnishing belt also assists in adapting the belt to irregular shapes of the work, inasmuch as the separate belt sections are permitted to independently rise and fall in accordance with the work contour over which they pass. The belt 50 is raised and lowered to suit the height of the work being acted on by adjustment of the hand wheel 85 which causes a turning of the shaft 80 and pinions 79 in mesh with the respective rack teeth 78 of the two slide-bars 58 that are located at opposite sides of the burnishing unit. The belt may also be adjusted to suit the transverse configuration of the work-pieces so that it may either engage substantially flat against the top of a flat piece of work or engage along one side edge or the other thereof, or may be made to engage a flat but slanting work piece. The tilting adjustment of the belt 50 for this purpose is accomplished by an adjustment of the hand wheel 72 which turns the screw 71 in engagement with one arm of the lever 68 and effects a raising or lowering of the link 67. The movement of this link is in turn imparted to the motor 61, rocker frame 54 and drums 51 carrying the belt 50. It is thus apparent that by adjustment of either or both of the hand wheels 72 and 85, the burnishing surfaces of the belts 50 may be raised and lowered or transversely rocked with respect to the work so as to have the desired burnishing engagement therewith, and the two belts may be set at different angles to engage different sides of an angular work-piece. The movement of the conveyor is slow and preferably substantially continuous during a burnishing action so that the work-pieces are slowly moved under the successive belts 50 lengthwise thereof while immersed in the liquid abrasive. The belts 50 are preferably moved in opposite directions with respect to the direction of movement of the work, so that the piece is engaged first by the multiplicity of fingers moving in one direction and later in the other and all surfaces thereof are given an equal burnishing treatment.

After the burnishing operation, the work-pieces leave the liquid at the right end of the lower runway, travel up the incline at such end and enter the upper runway 11. In this movement, the abrasive liquid drains from the work and conveyor and flows back into the lower abrasive containing compartment 4. In the upper run the work is carried through the spray tunnel 14 and washed of any clinging burnishing material and then passes to the left of the tunnel in position to be removed from the conveyor and another work-piece substituted therefor.

We wish it understood that our invention is not limited to any specific construction, arrangement or form of the parts, as it is capable of numerous modifications and changes without departing from the spirit of the claims.

What we claim is:

1. In a machine of the class described, a burnishing compartment, a burnishing liquid in said compartment, means for moving articles to be burnished through said compartment in submerged relation to said liquid, a rockable frame, means mounting said frame for said rocking movement, burnishing means carried by said

frame and adapted to have frictional engagement with the articles when moving through said liquid, means carried by the frame for driving said burnishing means to have burnishing movements lengthwise of the movement of said first means, means connected to said frame and operable to impart predetermined rocking movements thereto, and means operable to adjust said frame mounting means to raise and lower its rocking axis.

2. In a machine of the class described, a burnishing compartment, a burnishing liquid in said compartment, means for moving articles to be burnished through said compartment in submerged relation to said liquid, a frame rockable about a substantially horizontal axis, means mounting the frame for said rocking movement, an endless belt burnishing means carried by said frame at one side thereof and adapted to have one run of its belt in frictional engagement with the articles when moving through the liquid, the belt run being lengthwise of said movement, a motor mounted on said frame for driving said burnishing means and serving partially at least as a counterbalance therefor, and means connected to the frame and operable to rockably adjust it and hold it in adjusted position.

3. In a machine of the class described, a burnishing compartment, a burnishing liquid in said compartment, means for successively moving articles to be burnished through said compartment in submerged relation to said liquid, a rockable frame, means mounting the frame for rocking movement, two shafts projecting in parallel relation from one side of said frame, pulleys on said shafts, a burnishing belt mounted on said pulleys for engagement at one side of said pulleys with articles in their movement through the liquid, the movement of the articles being lengthwise of a run movement of said belt, drive means for one of said shafts mounted on the frame at the opposite side of its rocking axis to said pulleys and belt, and means connected to the frame and operable to rockably adjust it and hold it in adjusted position.

4. In a burnishing machine having a compartment containing a burnishing liquid through which an article to be burnished is conveyed in submerged relation to the liquid, a burnishing belt having a run operating against a conveyed article lengthwise of its movement and while submerged in the liquid, said belt having on its outer surface a multiplicity of small pliable burnishing projections and also having pliable diagonally disposed liquid moving cross flanges in longitudinally spaced relation thereon, and means for guiding and driving the belt.

5. A combination as called for in claim 4 wherein the belt is divided into separate sections disposed side by side transversely of the belt and capable of relative movements during a lengthwise run thereof intermediate the guiding means whereby to accommodate each section to the article surface engaged thereby.

6. In a machine of the class described, a horizontally elongated burnishing compartment, a burnishing liquid therein, means for conveying successive work articles into, through and out of said compartment submerged in said liquid and in substantially a linear run, a plurality of burnishing belts, means for mounting and guiding the belts to have runs lengthwise of the article movement and in successive burnishing engagement with conveyed articles, a rockable frame carrying said mounting means, means mounting said frame for vertical rocking movements, drive means for each belt carried by said frame and operative to impart opposite directions of movement to successive belts, and means for adjusting said frame and the parts carried thereby about its rocking axis.
- 15 7. In a machine of the class described, a horizontally elongated burnishing compartment, a burnishing liquid therein, means for conveying successive work articles into, through and out of said compartment submerged in said liquid and in substantially a linear run, a plurality of burnishing belts, means for mounting and guiding the belts to have runs lengthwise of the article movement and in successive burnishing engagement with conveyed articles, and drive means for each belt operative to impart opposite directions of movement to successive belts.
- 20 8. In a burnishing machine having a burnishing compartment, means to convey articles through said compartment, means to wet said conveyed articles with a burnishing liquid, a burnishing belt having a run operating against a conveyed article lengthwise of its movement and while wet with said burnishing liquid, said belt having on its outer surface a multiplicity of small pliable burnishing projections extending therefrom, and means for guiding and driving the belt.
- 25 9. In a machine of the class described, a horizontal elongated burnishing compartment, means for conveying successive work articles into, through and out of said compartment in a substantially linear run, means to wet said articles with a burnishing liquid, a plurality of burnishing belts, means for mounting and guiding the belts to have runs lengthwise of the article movement and in successive burnishing engagement with wet conveyed articles, and drive means for each belt operative to impart opposite directions of movement to successive belts.
